ELECTRORESPONSIVE DEVICE

Viktor Aigner, Steglitz, and Bernhard Nerlich,
Berlin-Charlottenburg, Germany, assignors to
General Electric Company, a corporation of
New York

Application May 15, 1940, Serial No. 335,424
In Germany March 6, 1939

12 Claims. (Cl. 175—294)

Our invention relates to improvements in electro-responsive devices which operate only at or near a predetermined point of the wave of an alternating electric quantity and more particularly to such devices for the control of switches conducting alternating current whereby to effect circuit interruption at or near the zero point of the current wave.

It is well known that, in order to minimize the destructive effect on contacts in the circuit-opening operation of switches in heavy current or high voltage alternating current systems, it is desirable to effect the interrupting operation at the zero point of the current wave. This requirement is particularly exacting when such switches are used for the remote control of groups of similar consumers by opening operations in a predetermined time sequence for effecting certain switching orders. Such keying switches, as they are sometimes called, have, dependent on the number of the switching orders, to perform a large number of switching operations. Consequently, the life of such switches can be greatly increased if the circuit interruptions can be effected at the zero point of the current wave. In such a case the wear on the contacts becomes theoretically zero and practically very small. Furthermore, when the switches are opened for the purpose of removing faults, such as short-circuits, between conductors or between a conductor and ground, the switch opening operation is facilitated and the wear on the contacts reduced if the interruption is effected at the zero point of the current wave.

The time between the releasing or tripping impulse for the switch and the actual interruption may be an integral multiple of a half wave. Thus, for example, in pressure-operated switches, it is possible to keep the pressure substantially constant by the use of sufficiently large compressed air storage tanks. The problem then is, in these cases, to give the releasing or tripping impulse at or near the zero point of the current wave.

In accordance with our invention, we provide an improved electro-responsive device whose range of operation can be definitely and closely controlled at or near a predetermined point of an alternating electric quantity. Another object of our invention is to provide an improved arrangement for effecting the opening of switches, conducting alternating current and having a substantially definite opening time, only at or near the zero point of the alternating current wave. These and other objects of our invention will appear in more detail hereinafter.

Our invention will be better understood from the following description when considered in connection with the accompanying drawing, and its scope will be pointed out in the appended claims.

In the accompanying drawing, Fig. 1 illustrates diagrammatically an embodiment of our invention, and Fig. 2 is a curve diagram explanatory of the embodiment of our invention shown in Fig. 1.

In the embodiment of our invention shown in Fig. 1, an alternating current circuit 3, shown in single line diagram for simplicity, is provided with a suitable circuit interrupting switch which is illustrated simply as a circuit breaker 4 of the latched closed type. The tripping or releasing impulse may be effected by a trip coil 5 to cause the opening of the circuit breaker for keying purposes, the interruption of short-circuits, or otherwise.

In order to effect the tripping or releasing impulse at the zero point of the current wave, we provide, in accordance with our invention, an electro-responsive device comprising a movable armature 6, which may be pivoted as at 7, and two magnetic circuits including cores 8 and 9 for controlling the movement of the armature. In accordance with our invention, one of the magnetic circuits 8 is energized in accordance with an alternating current derived from the circuit 3 by suitable means, such as a current transformer 10, connected in this circuit and to the magnetizing winding 11 on the core 8. Further, in accordance with our invention, the other magnetic circuit 9 is energized at the desired time in accordance with a direct current which is dependent on the current in the circuit 3 and which may be obtained from a full wave rectifier 12 connected to the magnetizing winding 13 on the core 9. The armature 6 is under the bias of a spring 14 which tends to urge the armature away from the poles of the magnetic core 8 against a stop 14'. The load circuit of the rectifier 12 may be provided with a smoothing condenser 15, as shown. The movement of the armature 6 is arranged to control circuit-closing contacts 16 and 17. The closing of contact 16 may energize the trip coil 5 directly or through the contacts of an auxiliary relay 18 connected to the source 19. The closing of the contacts 17 eliminates the effect of the coil 11 on the armature 6 as long as these contacts remain closed since they are arranged to short-circuit the coil 11.

In order to control the movement of the armature 6 so as to effect the tripping impulse at the time desired, we provide means for normally rendering the magnetic circuit 8 ineffective to

exert any attractive effort on the armature. As shown, this means comprises contacts 20 normally closed by a movable contact-controlling member 21 which may be actuated either manually or otherwise, as, for example, by electromagnetic means examples of which are well known to the art. As shown, the contacts 20 are arranged in a circuit connected across the rectifier 12 so that, when these contacts are closed, the rectifier is short-circuited and no current is supplied to the magnetizing winding 13. When the circuit breaker 4 is open, the spring 14, as heretofore mentioned, urges the armature 6 away from the poles of the core 8. If, however, the circuit breaker 4 is closed and current is flowing in the circuit 3, a corresponding secondary current appears in the current transformer 10 which, flowing by way of the closed contacts 20, energizes the winding 11, thus tending to attract the armature 6 upwards to the poles of the core 8.

When a releasing impulse or tripping action is to be given, the contacts 20 are opened by moving the circuit-controlling member 21 upwards. Under these conditions, current flows from the secondary side of the current transformer 10 through the rectifier 12 and, therefore, as direct current in the direction of the arrow 22 through the coil 13 but, as alternating current, through the coil 11. The condenser 15 smooths the rectified current to such an extent that a current, corresponding to the curve *b* in Fig. 2, flows in the coil 13. Through the coil 11, however, there is flowing an alternating current according to the curve *a* of Fig. 2.

In accordance with our invention, the winding ratio of the two coils 11 and 13 is so dimensioned that the flux due to the direct current *b* is equal to the flux due to the alternating current *a* at the desired predetermined distance or current value *c* of the straight line I—I from the abscissa axis O—O. When the alternating flux decreases below that due to the current value *c*, the direct flux and, therefore, its magnetomotive force preponderates and this continues during the time *x*. When this condition occurs at a time after the release impulse is given by the opening of the contacts 20, the armature 6 moves downward and closes its contacts 16 and 17. The closing of the contact 17 short-circuits the winding 11 so that the armature 6 remains in the downward contact closed position until after the disappearance of current in the circuit 3 by reason of the opening of the circuit breaker 4 whereupon the spring 14 restores the armature to the unattracted position.

Since currents, which are in a fixed relation to each other flow through the coils 11 and 13, the time interval *y* between the instant at which the direct current preponderates and the zero point of the alternating flux is constant and independent of the magnitude of the current in the circuit 4 prevailing at the time. If the straight line I—I is placed at half the current amplitude, this means that the direct current ampere turns correspond to half the value of the maximum alternating current ampere turns. Then the distance *y* corresponds to an angle of 30 degrees independently of the peak value of the alternating current prevailing at the time.

Accordingly, the armature 6 is always actuated downwardly at a predetermined point of the current wave and closes the release contact 16. Since the opening time of the switch 4 can be adjusted to a desired value, the interruption takes

place at or near the zero point of the current wave.

The curve diagram in Fig. 2 shows the built up or steady state condition of the currents and fluxes in the magnetic circuits 8 and 9 after the opening of the contacts 20. In order to avoid any possibility of false operation during the gradual increase of the direct current to its steady state value, we provide means for preventing movement of the armature under the effect of the magnetic circuit 8. As shown, this means mechanically locks the armature against downward movement and comprises a latch 23 under the control of an electromagnetic device 24 which may be energized from a source 25 through contacts 26 under the control of the movable circuit-controlling member 21. Thus, when the movable circuit-controlling member 21 is moved upward to give the tripping or release impulse, it also energizes the electromagnetic device 24 which preferably has a suitable time delay sufficient to insure the release of the latch only after the direct current in the coil 13 has reached a steady state value.

While we have shown and described our invention in considerable detail, we do not desire to be limited to the exact arrangements shown, but seek to cover in the appended claims all those modifications that fall within the true spirit and scope of our invention.

What we claim as new and desire to secure by Letters Patent of the United States is:

1. An electroresponsive device comprising a movable armature and means for effecting a predetermined movement of the armature near a predetermined point of the wave of an alternating electric quantity comprising means for exerting two opposing magnetic effects on said armature respectively dependent on an alternating current and a direct current derived from said alternating electric quantity and having a predetermined fixed magnitude relation to each other.

2. An electroresponsive device comprising a movable armature and means for effecting a predetermined movement of the armature near a predetermined point of the wave of an alternating electric quantity comprising means for exerting two opposing magnetic effects on said armature respectively dependent on an alternating current and a direct current derived from said alternating electric quantity and having a predetermined fixed magnitude relation to each other, and means for controlling the application of the magnetic effect due to said direct current.

3. An electroresponsive device comprising a movable armature and means for effecting a predetermined movement of the armature near a predetermined point of the wave of an alternating electric quantity comprising means for exerting two opposing magnetic effects on said armature respectively dependent on an alternating current and a direct current derived from said alternating electric quantity and having a predetermined fixed magnitude relation to each other, means for controlling the application of the magnetic effect due to said direct current, and means for preventing movement of the armature by the effect due to said direct current until after the direct current effect has been applied long enough to reach its steady state value.

4. An electroresponsive device comprising a movable armature and means for effecting a predetermined movement of the armature near a predetermined point of the wave of an alternating

electric quantity comprising two magnetic circuits for controlling the movement of the armature, and means for respectively energizing said two magnetic circuits by an alternating current quantity and a direct current quantity both derived from said alternating electric quantity and having a predetermined fixed magnitude relation to each other.

5. An electroresponsive device comprising a movable armature and means for effecting a predetermined movement of the armature near a predetermined point of the wave of an alternating electric quantity comprising two magnetic circuits for controlling the movement of the armature, means for respectively energizing said two magnetic circuits by an alternating current quantity and a direct current quantity both derived from said alternating electric quantity and having a predetermined fixed magnitude relation to each other, and means for controlling the application of said direct current quantity.

6. An electroresponsive device comprising a movable armature and means for effecting a predetermined movement of the armature near a predetermined point of the wave of an alternating electric quantity comprising two magnetic circuits for controlling the movement of the armature, means for respectively energizing said two magnetic circuits by an alternating current quantity and a direct current quantity both derived from said alternating electric quantity and having a predetermined fixed magnitude relation to each other, means for controlling the application of said direct current quantity, and means for preventing movement of the armature in response to said direct current quantity energization until the flux due to the direct current has reached its steady state value.

7. Electroresponsive apparatus for effecting the release of an electric switch conducting alternating current near the zero point of the current wave comprising a movable armature, two magnetic circuits for controlling the movement of said armature, and means for respectively energizing said two magnetic circuits by an alternating current and a direct current both dependent on the current conducted by the switch and having a predetermined fixed magnitude relation to each other.

8. Electroresponsive apparatus for effecting the release of an electric switch conducting alternating current near the zero point of the current wave comprising a movable armature, two magnetic circuits for controlling the movement of said armature, means for respectively energizing said two magnetic circuits by an alternating current and a direct current both dependent on the current conducted by the switch and having a predetermined fixed magnitude relation to each

other, and means for rendering one of said magnetic circuits ineffective until release of the switch is desired.

9. Electroresponsive apparatus for effecting the release of an electric switch conducting alternating current near the zero point of the current wave comprising a movable armature, two magnetic circuits for controlling the movement of said armature, means for respectively energizing said two magnetic circuits by an alternating current and a direct current both dependent on the current conducted by the switch and having a predetermined fixed magnitude relation to each other, means for rendering one of said magnetic circuits ineffective until release of the switch is desired, and means for preventing movement of said armature under the effect of said one of said magnetic circuits until the flux in said circuit has reached a predetermined value.

10. In an electroresponsive device comprising a movable armature and means for effecting a predetermined movement of the armature near a predetermined point of the wave of an alternating electric quantity comprising means for exerting two opposing magnetic effects on said armature respectively dependent on two currents derived from said alternating electric quantity and having a predetermined fixed magnitude relation to each other.

11. An electroresponsive device comprising a movable armature and means for effecting a predetermined movement of the armature near a predetermined point of the wave of an alternating electric quantity comprising means for exerting two opposing magnetic effects on said armature respectively dependent on two currents derived from said alternating electric quantity and having a predetermined fixed magnitude relation to each other, and means for controlling the application of the magnetic effect due to one of said currents.

12. An electroresponsive device comprising a movable armature and means for effecting a predetermined movement of the armature near a predetermined point of the wave of an alternating electric quantity comprising means for exerting two opposing magnetic effects on said armature respectively dependent on two currents derived from said alternating electric quantity and having a predetermined fixed magnitude relation to each other, means for controlling the application of the magnetic effect due to one of said currents, and means for preventing movement of the armature by the effect due to said one of said currents until after the effect of said current has been applied for a predetermined time.
